NAILING MACHINE

Johan A. Johansson, Berkeley, Calif.

Application June 25, 1940, Serial No. 342,295

7 Claims. (Cl. 1—46)

The invention relates to a nailing implement for continuous operation for nailing a succession of floor boards, or similar elements, in place.

A general object of the invention is to provide an improved nailing unit having a nail hopper and provided with a motor which effects the operative disposal and release of a swinging hammer and the positioning of a nail from the hopper for its driving by the released hammer.

A more specific object is to provide an improved hammer-actuating means for a nailing unit of the character described.

Another object is to provide an improved and particularly simple nailing head having a single nail-driving element which is readily dismountable merely by lifting it from its operative place.

Another object is to provide a particularly simple and effective device for automatically insuring the supply of solely one nail at a time to the head.

A further object is to provide an improved means for mounting the nails in alignment in a slideway which conveys them to the head.

The invention possesses other objects and features of advantage, some of which, with the foregoing, will be set forth or be apparent in the following description of a typical embodiment of my invention, and in the accompanying drawings, in which,

Figure 1 is a side view of a nail-driving implement embodying my invention and having the hammer thereof in raised position.

Figure 2 is a plan view of the implement with part broken away on the line 2—2 in Figure 1.

Figure 3 is a sectional elevation at the line 3—3 in Figure 2, and shows the relation of the parts when the hammer is resting upon a nail-driving plunger of the unit.

Figure 4 is an enlarged sectional elevation on the broken line 4—4 in Figure 1.

Figure 5 is an enlarged and fragmentary section taken at the line 5—5 in Figure 1.

Figure 6 is an enlargement and fragmentary section taken at the broken line 6—6 in Figure 1.

Figure 7 is a vertical section through the head of the hammer.

Figure 8 is a perspective view of an impact member used in the hammer-head.

Figure 9 is a sectional view of a nail-feeding hopper of the unit, the view being taken at the line 9—9 in Figure 1.

Figure 10 is a side view of the hopper, the side cover thereof being removed, and parts of the structure being broken away.

Figure 11 is a section of the hopper taken at the line 11—11 in Figure 10.

Figure 12 is a fragmentary section of the tool head, and is taken at the line 12—12 in Figure 2.

Figure 13 is a stepped section at 13—13 in Figure 12.

Figure 14 is a perspective view of certain nail-releasing elements of the head.

As particularly shown, the features of my invention are incorporated in the structure of a nailing unit having a swinging hammer 16 operative against a nail-driving plunger 17 mounted in a nailing head 18 to which nails N are automatically supplied from a hopper 19. The aforesaid elements are carried on a unitary frame which also mounts an electric motor 21 which is operatively connected to the hammer and hopper for effecting the operations of the latter elements.

The relatively long and narrow frame for the present embodiment of my invention comprises a generally triangular plate member 22 which directly supports the motor 21 intermediately thereon and carries the head 18 at its forward point. Side frame members 23 extend rearwardly from the rear corners of the member 22 to connections with a cross-member 24, whereby the members 22 and 23 and 24 jointly provide a base portion of the frame. A pair of support feet 25 is provided at the member 24, and a single support foot 26 is provided at the forward portion of the member 22, whereby said feet jointly provide the plane of support for the unit. Since the present unit is to be moved over placed boards to be nailed down, the feet 25 and 26 are preferably provided with anti-friction members to engage the boards; as shown, the contact elements of the feet comprise ball casters 27. For a reason to be hereinafter brought out, the forward frame portion is preferably supported on a compression spring 26' which is operative between the foot 26 and the plate 22 to resiliently support the front portion of the unit.

Spaced frame posts 28 extend upwardly from the rear end of the frame and are connected at their tops by a cross-member 29, and spaced posts 31 extend upwardly from the forward ends of the side frame members 23 and are connected at their tops by a cross-member 32. A longitudinal side member 33 connects the upper end of each post 31 with the corresponding post 28. For providing a frame having the desirable qualities of lightness and strength, certain of the frame members may be of angle section, as shown. In the present instance, the members 22 and 31 and

32 and 33 are provided as integral parts of a single casting, rather than the elements of a built-up structure.

A shield plate 34 substantially closes the rearward face of the frame portion provided by the members 24 and 28 and 29, and a control switch 35 for the motor 21 may be mounted on the plate. A bracket arm 36 is mounted at the rear of the frame and provides an upright handle 37 for use in moving the implement about. The power wires 38 to the switch 35 are shown as extending axially through the handle 36, and the wires 39 from the switch to the motor extend longitudinally through the frame in any path which is clear of moving parts.

The rear upper cross-member 29 of the frame mounts mutually parallel wrist pins 41 and 42 between spaced pairs of ears 40 of the member, said wrist pins rotatively carrying gears 43 and 44 which are arranged for a constant mutual meshing thereof. The gear 43 is fixed at the rear end of the handle 45 of the hammer 16, and the gear 44 is fixed at one end of a depending arm 46 which has its other end connected by a relatively strong tension spring 47 with an anchorage member 48 fixed on the bottom frame member 22. The arrangement is such that an upward swinging of the hammer about its pivotal axis at the pin 41 to position its head 49 for a working blow against the nail-driving plunger 17 is yielding resisted by the tension spring 47 which stores up energy for swinging the hammer in a working stroke against the plunger when it is released.

Means are preferably provided to adjustably vary the effective tension of the spring 47 for its hammer-operating action; as shown, said means comprises the provision for the adjustable mounting of the anchor member 48 on the frame member 22. In the present structure, the member 48 is provided with rows of holes 51 for selectively receiving cap screws 52 threadedly engaged in the member 22 whereby the effective resistance of the spring 47 may be adjustably varied to meet variable operating requirements for the hammer, due, for instance, to differences in the hardness and/or thickness of the boards to be nailed.

It will now be noted that a shaft 53 is journaled in and between the upper side frame members 33 and carries a cam member 54 having a pair of like and oppositely directed arms 55 extending from a hub 56 which is rotatable by and with the shaft 53. The arms 55 are arranged for rotation in a common plane parallel to the plane of swinging of the hammer handle 45, have their forward edges 57 curved rearwardly and spirally to their free extremities, and have their rearward edges 58 convexedly curved. As the hub 56 is rotated, the edges 57 of the cam arms 55 are successively operative against a roller 59 mounted on the hammer handle 45 to swing the hammer upwardly against the resistance of the spring 47 until the arm extremities are reached and the hammer is released for working strokes under the influence of the spring. An end of the cam shaft 53 which extends from one side of the frame carries a gear 62 which constantly meshes with a gear 63 carried on the power output shaft of the motor 21 whereby the cam 54 may actuate the hammer 16 in the described manner.

As shown, the hammer handle 45 is longitudinally forked from its pivoted end, and in the plane of operation of the cam arms, for freely

receiving said arms in the slot between the fork sides 60. The extremities of the fork sides 60 have the gear 43 fixed to and between them, and a shaft 61 fixed to and between the fork sides 60 rotatably carries the roller 59 against which the cam edge faces 57 are operative for raising the hammer into striking position. This arrangement is understood to provide for the operation of the cam 54 in the central plane of swinging of the hammer handle and so minimize friction in the operation of the hammer. The roller 59 is preferably so positioned on the handle 45 that it lies directly above the shaft 53 when the hammer is fully lowered as in Figure 3.

15 A clutch means is provided for rendering the cam 54 inoperative while the motor 21 is operating. As particularly brought out in Figures 5 and 6, the shaft 53 is divided at a point thereof between the cam hub 56 and the supporting frame member 33 nearest the gear 62 to provide abutting sections 64 and 65 which respectively have the cam and gear fixed to them, the clutch means being cooperative between said shaft sections. The shaft sections 64 and 65 are stepped together at their mutually abutting ends, whereby the shaft bearings in the upper side frame members 33 may fully journal the shaft. Axial separation of the shaft sections is prevented by a thrust plate 66 mounted on the frame members 33 which provides the bearing for the cam section 64, and a radial shoulder 67 provided on the shaft section 65 in close opposition to the inner end of the bearing sleeve for the section.

35 A pin 68 is non-rotatably slidable in a complementary bore extending axially through the cam hub 56 and has one end normally engaged in a segmental socket 69 provided in the opposed end portion of the shaft section 65 which has approximately the same diameter as the opposed hub end. A compression spring 71 is operative 40 between the other end of the pin 68 and the plate 66 for constantly urging a disposal and retention of the pin in the socket 69 as a releasable clutch means providing for a driving of the cam 54 by the motor. An annular groove 72 of uniform cross-section is provided in the hub 56 of the cam 54 to extend into the bore which receives the pin 68, and said pin is provided with a notch 73 in its outer side, said notch having a major portion thereof in advance of the groove when the pin is operatively engaged in the socket.

55 A member 74 is provided for swinging in a fixed plane for engagement in the hub groove 72 to wedgedly engage the inner side of the pin notch 73 for withdrawing the pin 68 from its engagement in the socket 69 of the shaft section 65 and so stop a rotation of the cam and the actuation of the hammer 16 while the shaft portion 65 rotates. As is brought out in Figures 1 and 4 and 5 and 6, the member 74 comprises the free end of an arm 75 having its other end provided with an eye 76 which receives a pivot pin 77 fixed to and between the lower side frame members 23. The member 74 is provided with an arcuate notch at its groove-engaging edge, and its groove-engaging portion 78 at said notch is tapered as a wedge longitudinally thereof in such manner that the working rotation of the hub is toward the wedge base to provide for the functioning of the wedge against the inner side of the pin notch 73 to withdraw the pin 68 and so disconnect the cam for its stopping when the member 74 has been swung to dispose its wedge portion 78 in the

hub groove; this release of the cam is arranged to occur when the hammer is in the lowered position shown for it in Figure 3.

Means are provided for swinging the arm 75 to operatively engage the wedge 78 in the hub groove 72 for withdrawing the clutch pin 68 against the resistance of the spring 71. As shown, a pull rod 79 extends forwardly from the arm 75 which disposes the member 74 at the rear side of the hub for swinging the arm forwardly against the resistance of a spring 81 which extends from the arm to an anchorage on the adjacent upper side from member 33. At its forward end, the link 79 is connected to one arm of a lever 82 pivoted on a bracket member 83 for rocking about an upright axis, said bracket being mounted on a forward upright frame post 31 near its top; as shown, the pin-displacing device is disposed to the right of the plane of operation of the arm lifting cam 54.

By particular reference to Figure 6, it will be seen that the bracket 83 provides a tubular and forwardly directed handle 84 through which a push rod 85 slidably extends to a connection at its rear end with the other end of the lever 82. The forward handle 84 is arranged for use cooperatively with the rear handle 37 for manipulating the tool over the work, and the present clutch control device is so arranged that a mechanic may, while grasping the handle 84, press in on the push rod 85 to displace the member 74 for causing a cessation of the hammer's actuation which normally occurs whenever the motor is operating.

Should it be desired to stop the hammer from actuating while the motor is operating and without requiring the continued pressure of the mechanic's hand on the rod 85, a pin 86, or other pinlike member such as a nail, may be engaged through and between holes 87 and 88 respectively provided through the handle and thrust rod 85, said holes registering only when the rod 85 is pushed in to disengage the clutch pin 68.

It will now be noted that the nailing head assembly 18 includes an elongated block 87 provided with a uniform longitudinal bore 88 in which the plunger 17 is closely and slidably engaged. The block 87 is suitably fixed to the forward end of the frame member 22 with the plunger 17 operative in fixed angular relation to it; as shown, a lateral block extension 89 is bolted to the front end of the member 22 to dispose the plunger in perpendicular relation to the bottom plane of the frame and in the line of operation of the hammer 16. At its upper end, the plunger 17 is provided with a striking head portion 91 which is larger than the plunger body, and a compression spring 92 encircling the plunger is constantly operative between the head 91 and a seat ring 90 which freely encircles the plunger above the upper block end to urge the disposal of the plunger to the raised position thereof shown in Figure 1.

At its lower end, the bore 88 slidably receives the upper and smaller portion of a cylindrical nose-piece 93 having its exterior stepped to provide a shoulder which may engage the lower end of the block 87 to limit the extension of the nose-piece into the bore 88. The element 93 provides a guide for a nail to be driven, and is provided with an axial bore 94 which is just large enough to permit the free passage of a nail N therethrough, said nail having a head which extends beyond the cylinder of its shank. To facilitate the entry and centering of a nail

therein, the upper end of the bore 94 is conically enlarged or counterbored. The normal spacing of the lower end of the head block 87 from the base plane of the foot spring 26 is preferably such that the nose-piece 93 gravitally rests on the board to be nailed down without bearing the front-end weight of the unit and with its shoulder relatively close to the lower block end; in this manner, a nail being driven is constantly enclosed at the floor line against its lateral bending therest, while the nose-piece limits any downward movement of the nailing head.

A drive pin 95 is mounted in the lower end of the plunger 17 in the common axial line of the bores 88 and 94 of the block and nose-piece respectively. The pin 95 is arranged to enter the bore 94 behind a nail therein for driving the nail through and beyond the latter bore to set (countersink) its head in the floor to a degree determined by the working stroke of the plunger as limited jointly by the striking of the top of the nose-piece by the lower plunger end and by the extension of the pin beyond the lower plunger end. Preferably, and as shown, the pin 95 is threadedly engaged in the plunger to provide for adjusting its effective length to determine the set of a driven nail. When the plunger is in raised position, sufficient space is left below and about the drive pin 95 to permit the introduction of a nail laterally into the bore 88 for its gravity fall into the bore 94 of the nose-piece 93 to have its point rest on the underlying floor board for its subsequent driving therewith.

Means are provided whereby the force of the plunger-raising spring 92 is exerted solely between spaced points of the plunger when the plunger is in its fully raised position, with the purpose of permitting a free lifting of the plunger out of the head bore 88 in which it is arranged to be retained solely by gravity. As particularly shown, the plunger is provided with a longitudinal slot 96 extending upwardly from a point of the plunger shank which is below the top of the head block 87 when the plunger is raised, the slot 96 being of uniform cross-section. The slot 96 constantly and freely receives a pin 97 comprising a lateral extension of a member 98 which is restrained to movement solely axially of and with respect to the plunger. When the plunger is fully raised, the spring 92 is operative to dispose the seat-ring 90 at a limiting distance from the plunger head as determined by the engagement of the pin 97 with the bottom end of the slot, the spring force then being entirely coactive, through the ring 90 and the member 98, between the relatively fixed plunger parts comprising the head 91 and the stop provided by the bottom end 99 of the slot 96.

As particularly illustrated, the member 98 is cylindrical and is slidable in a complementary guide socket 101 extending into the head block 87 from the upper end thereof in parallel relation to the bore 88 and of a depth slightly exceeding the length of the member. A slot 102 connects the socket and bore in mutually radial relation thereto for the extension of the pin 97 therethrough to permit a disposal of the member 98 entirely below the block top to provide for the engagement of the seat-ring 90 against the upper block end to support the raised plunger upon the spring 92. This arrangement permits a working depression of the plunger 17 through the seated ring 90 against the full re-

sistance of the spring 92, it being understood that the resistance of said spring is preferably but little more than is required to insure the full raising of the plunger above the washer 99 after a working stroke thereof, and that the length of the plunger slot is such as to permit a full working stroke of the plunger without contact of its upper end with the pin 97. As shown, the slot 102 extends outwardly of the socket 101 to slidably receive an extension 103 of the member 98 which, with the pin 97, cooperates with the slot sides to prevent a rotation of the member to avoid any engagement of the pin 97 with the sides of the plunger slot 96 and so prevent any frictional wear of the pin or slot sides as the plunger is reciprocated in the head.

When the plunger 17 is released after a working stroke thereof, it is lifted upward behind the hammer head by the action of the spring 92 until the pin 97 of the member 98 is struck by the slot bottom 99 to engage the member against the seat ring 90 and finally produce the normal conditions for the raised plunger. When the member 98 first strikes the ring 90, the upward movement of the plunger is checked and cushioned by the reaction of the spring 92 against the ring to bring the plunger to rest. If the inertia of the plunger should be sufficient to lift the ring from its seat in the head block during the stopping of the upward plunger motion, the assembly will subsequently fall by gravity to reseat the ring on the head block as the support for the plunger assembly.

The shock and noise of impact during a working stroke of the hammer are minimized by providing the hammer head 49 with a non-resonant and slightly yielding striking face 105. As shown, the head 49 is generally tubular and provides cylindric bore portions 106 and 107 above and below an intermediate cross partition 108 having a central opening 109 therein. An impact member 111 is frictionally engaged in the lower bore 107 to provide the working face 105 for engaging the plunger head 91, said member preferably comprising a cylindrical roll of rawhide or some other material which is relatively non-resonant and non-resilient. A disc 112 is preferably installed between the inner end of the member 111 and the partition 108 whereby removal of the member 111 for its replacement may be readily effected by operatively applying a suitable punch (not shown) against the disc through the opening 109 of the partition 108. The head space or bore above the partition 108 is arranged to receive an appropriate weight; as shown, a weight member 113 is threadedly mounted in the bore 106, it being understood that the weight provided in said bore may be large or small to satisfy different operating conditions for the nailing machine.

Referring particularly to Figures 12 and 14, it will be noted that a hole or bore 114 extends obliquely upwardly in the head block 27 from the top of the nose-piece 93 within the plunger-receiving bore 86 to an opening at the rear exterior of the block for the gravity and point-down delivery of a nail N into the nose-piece bore 94 from a chute or slide-way assembly 115 from which nails are arranged to be automatically supplied within the head one at a time and just before each plunger operation. A horizontal guideway is provided across the upper end of the hole 114 and reciprocally carries a nail-releasing plate member 116 which is normally disposed to hold back a line of nails in the slideway 115 and is longitudinally displaceable to release but one nail at each nail-

releasing displacement thereof. As shown, the guideway for the member 116 is cooperatively provided by and between the head block and a member 117 fixed thereto and providing spaced ears 5 118 on which the lower end of the slideway 115 is mounted.

The slideway 115 essentially comprises opposed vertical plates 119 mutually spaced to freely receive the nail shanks between them while the nail 10 heads rest on and span their upper edges which define a slot 120 inclined for gravity movement of the nails therealong and toward the nailing head. The slideway thus provided is arranged to normally support the line of nails with the upper 15 end portion of the forward nail N against the outer and rearward face of the member 116 while the nail shank depends in the upper end of the hole 114. The member 116 is notched from below to provide a nail-escape opening 121 at a point to 20 one side of its area which normally bars a delivery of nails from the supply slideway, and means are provided for insuring the escape of but one nail at a time when the member 116 is shifted to dispose the opening 121 in alignment with the line of 25 nails. As shown, a sharpened separating arm 122 on the member extends across the opening from its side opposite said nail-retaining area, and is so spaced from the member that its point may engage between the leading and second nails of the 30 line as the member is shifted whereby to permit the escape of the leading nail through the notch 121 and hold back the rest of the nails. When the member 116 makes a return stroke, the new leading nail is released from behind the arm 122 to 35 move against the member 116 in preparation for a repetition of the described nail-feeding process.

Means are provided for actuating the nail-releasing member 16 in synchronism with the operation of the hammer. As particularly shown, a 40 rock shaft 123 is journaled in the frame longitudinally thereof, and below the level of the member 116, and carries upwardly extending radial arms 124 and 125 at its forward and rear ends respectively. The arm 124 comprises a plate having a longitudinal slot 126 therein which slidably and constantly receives a pin 127 extending fixedly from the member 116 whereby to provide in effect, a universal joint between the arm and member. A bell-crank lever 128 is pivoted to the top of the 45 upper frame portion at a forward point thereof and to one side of the plane of operation of the cam 54, said lever having an arm 129 providing a contact lip or edge 131 normally disposed in the path of movement of the working cam edges 57 by the appropriate action of a tension spring 132 on the lever.

The other arm 133 of the lever 128 is vertically slotted to freely receive the free end of the arm 126 of the rock shaft 123, and extends in such a 50 relation to the arm 129 that the shaft arm 125 may engage the inner side of the adjacent member 33 as a stop means for the arm when the member 116 is disposed to hold back the nails at the head 18. As shown, the spring 132 is operative between the free end of the arm 129 and an anchorage in an upper side from member 33 whereby it 55 yieldingly holds both the member 116 and the contact lip 131 in their normal positions. The arrangement is such that just before one cam arm is disposed to release the raised hammer for a working stroke, the other cam arm wedgedly engages the lip 131 and deflects the lever 128 to rock the shaft 123 to move the member 116 to release a nail for its arrival in the nose-piece 93 just before and substantially simultaneously with the

striking of the nail-driving plunger 17 by the hammer head.

As shown, the chute or slideway 115 slopes downwardly to the nailing head from within the chamber of the supply hopper 19 which is mounted on the frame to one side of the zone of operation of the hammer, and includes a means for automatically providing and maintaining a line of nails in the slideway, the various details of the hopper and said means being disclosed in Figures 9 to 11 inclusive. At the upper end of the slideway within in the hopper the side members 119 thereof have extensions directed upwardly and away from each other to provide the sides of a sloping trough 135 having its bottom comprising a continuation of the slot 120 to receive only the nail shanks as the rest of the slideway.

If nails are deposited at random in the trough 135, the points and shanks of some will fall into the trough slot 120 and so effect a positioning and support of such nails for their movement along the slideway to supply the nailing head. The remaining nails will slide downwardly in the trough to the lower trough end to fall into the underlying bottom of the hopper casing 137 from which they may be automatically redeposited in the trough through the operation of a rotary conveyor device which is provided for operation within the casing. It will be noted that the slideway is perpendicular to the head member 116 at its discharge end and may be straight or be laterally bent out of a straight line between the hopper and head as may be required to make the connection between the hopper and the head.

The casing 137 is of generally cylindric outline and a shaft 138 is journalled axially therein to extend through and from a fixed casing end 139. A gear 141 is provided on the extending end of the shaft 138, and the casing is so supported on the machine's frame by brackets 142 and 143 that the gear 141 constantly meshes with the gear 62 on the cam-operating shaft 53 for the actuation of the first shaft while the motor 21 is operating. A removable disc 144 having a peripheral flange 145 provides a closure for the other casing end, and is provided with a socket bearing 146 for receiving and centering the opposed end of the shaft 138 while its flange 145 fittedly receives the casing end. For a reason which will hereinafter become apparent, the bore of the casing tapers from a cylindric central portion thereof toward both its ends. Also, the end of the slideway 115 including the trough is above and oblique to the shaft 138 and extends through a casing opening 147 which is nearer the fixed casing end 139 than the slideway extremity in the casing.

A hub 148 is mounted on the shaft 138 adjacent the bearing 146 and carries a radial arm 149 provided with a terminal blade 151 extending axially of the shaft to a point centrally of the casing, and having its plane parallel to and generally radial of the shaft axis. The blade 151 is arranged for movement in the direction indicated in Figure 10 for pushing nails from the casing bottom around the opposed casing bore to a point at the top of the casing from which they may drop into the trough 135 for the mounted disposal of some of them in the slideway, it being noted that the outline and previously described oblique position of the trough are designed to permit this. The action is arranged to be rapid enough to centrifugally hold the nails to the overhanging bore portion substantially until the top thereof is reached by the nails.

As particularly disclosed, the arm hub 148 is free on the shaft 138 and is provided with axially directed clutch pins 152 which are normally disposed in the path of movement of complementary clutch pins 153 extending from the end face 154 of a sleeve member 155 fixed on the shaft 138. A compression spring 156 encircles the shaft and is yieldingly operative between an annular flange 157 at the shaft extremity and a seat provided by and within the hub 148 to constantly urge a disposal of the ends of the pins 152 against the end face 154 of the member 155. The mutually engageable sides of the pins 152 and 153 are complementarily bevelled whereby a holding of the blade 151 against rotation, as by jambing of nails between it and the casing bore, may automatically provide for a disengagement of the pins 152 from the shaft pins 153 by shifting the hub axially, said pins otherwise providing a clutch connection between the shaft 138 and the arm 149 of the conveyor blade 151; the operative arrangement is understood to constitute an overload release.

Nails may be supplied to the hopper 19 through a feed chute assembly 158 mounted on the hopper casing 137 and arranged to deliver nails therefrom through a horizontal slot 159 provided through the casing side at the bottom of the chute. The delivery of the nails to the hopper from the chute 158 is preferably at a controlled rate which approximates the average rate at which nails are to be driven by the present unit, and the described device for mounting nails from the hopper on the slideway 115 operates at a faster rate so that the slideway may generally be fully loaded to supply the nailing head 18.

As shown, the chute 158 comprises side walls 161 and 162 extending upwardly from a bottom 163 which slopes to a point of the casing at the bottom line of the slot 159 and is somewhat wider than said slot. The chute side wall 161 is fixed flat against the casing end wall 139 and the lower ends of the chute side wall 162 and bottom 163 are fixed directly to the side casing wall where they abut it; the chute thus extends rigidly from the casing, it being noted that the hopper support bracket 143 is operative between the machine frame and the upper chute end which is closed with a sloping wall.

A partition member 164 is mounted in and across the chute 158 for adjustment in its plane, which plane slopes rearwardly from the vertical to define an acute angle with the bottom plane of the chute. The straight bottom edge of the partition 164 is arranged to be variably spaced from the chute bottom to adjustably vary the rate of escape of nails beneath it from the chute space at its upper side. As shown, the partition 164 comprises a plate member 165 having like triangular side flanges 166 and a top flange 167 extending transversely from its lower (rear) side, all of said members of the partition being mutually connected at their abutting edges.

The side flanges 166 are provided with rectangular slots 168 immediately adjacent the plane of the lower face of the partition plate 165, said slots receiving therethrough a flat strap-like member 169 which has its ends secured to and between the chute sides 162. The slots 168 are longer than the width of the members 169 thereof to permit a guided shifting of the partition 164 in its plane, the bottom edge of said partition being spaced from the chute bottom and the partition being frictionally held in its adjusted position.

A false bottom member 171 is provided in the chute 158 and extends in its upper portion to a point spaced from the upper sides of the partition 164. The space 172 between the bottom members 153 and 171 receives the upper end of a plate member 173 which extends into the cavity of the casing 137 through the bottom portion of the slot 159 and is arranged for reciprocation in its plane by reason of the rotation of the shaft 138, it being noted that the plate 173 is guided for its movement in the plane of the space 172 by reason of its sliding engagement between the chute bottom members 163 and 171.

A flange or ear 174 extends transversely upwardly from the slide plate 173 at its inner end portion and is connected with the shaft 138 in a manner to provide for the reciprocation of the slide plate in its plane as the shaft rotates. As shown, an eccentric disc 175 is mounted on said shaft adjacent the plane of the flange 174 and engages in a complementary bore provided in one end of a member 176 having its other end pivoted to the flange 174 at a pivot pin 177, whereby a rotation of the shaft is arranged to effect a reciprocation of the plate 173. The portion of the slide plate 173 which is movable through the slot 159 is preferably roughened at its upper face, as by projection 178 on the plate.

By particular reference to Figure 10, it will be noted that nails N deposited in the chute portion above the partition 164 will, by reason of the natural vibration of the machine and the action of the plate 173 and its projections 178, assure a more or less orderly arrangement in the angular corner provided by the partition and the chute bottom in general parallelism with the bottom edge of the partition, and will be progressively freed to escape beneath said partition edge for travel down the plate 173 and through the opening 159 to thereafter fall from the plate into the underlying sloping portion of the casing for their final disposal in the zone of action of the conveyor blade 151.

It will be understood that the partition 164 is to be so adjusted that the rate at which nails are freed to escape beneath it is no less than the average rate of application of the nails by the implement, and has a distinct relation to the speed of operation of the conveyor blade. Also, the partition 164 and plate 173 are cooperative as a gate means for controlling the rate of discharge from the chute into the hopper.

From the foregoing description taken in connection with the accompanying drawings, the advantages of the construction and operation of the present nailing machine will be readily understood by those skilled in the art to which this invention appertains. While I have described the features and principles of operation of a structure which I now consider to comprise a preferred embodiment of my invention, I desire to have it understood that the showing is primarily illustrative, and that such changes may be made, when desired, as fall within the scope of the following claims.

I claim:

1. In an implement for movement on and over a succession of placed boards and the like to nail the same in place, an elongated frame of rigid structure, a head block fixedly mounted at the forward frame end and having a bore extending therethrough in fixed angular relation to the frame base, a nose member provided with a nail-receiving bore longitudinally therethrough and slidably engaged in said head block bore, and

extending below the block for its support on the underlying board, a step means on said member for limiting its extension into the block, a nail-driving plunger operative in the bore of the nose member, a single sliding support foot for the forward frame end, means resiliently supporting the forward frame end upon said forward support foot to normally dispose the head block above the stop means on the nose member, and a pair of sliding support feet for the rear frame end fixedly related thereto.

5 2. In an implement for nailing mutually co-planar boards and the like in place, a rigid frame for support on the placed boards for movement 15 thereover, a head block fixedly mounted on the frame and having a bore extended therethrough in transverse relation to the support plane of the frame, a normally raised and compressible plunger for actuation against a nail disposed therebelow 20 in the head block to drive the nail through an underlying board, a swinging hammer having its handle pivotally mounted on the frame and arranged for the action of its head against the head end of said plunger to drive the nail there- 25 with, a spring means constantly and yieldingly operative to resist a swinging of the hammer to a pre-determined position from which a working stroke of the hammer against the plunger is to be taken, a gear and lever connection between 30 the hammer handle and the spring, means adjustable to adjust the effective spring resistance, a cam means directly operative against the hammer handle in the plane of action thereof to dispose the hammer in said limiting position and 35 thereupon release it for a working stroke, and means to actuate said cam means.

3. In a nailing implement, a nail-driving plunger, a hammer movable independently of the plunger for striking actuation against said 40 plunger, a spring means operative to effect a working stroke of the hammer, a rotary cam operative to successively dispose the hammer for a working stroke thereof and release the hammer for the working stroke, a drive shaft for said cam, a power drive for said shaft, and a releasable clutch connection between the cam and shaft.

4. In a travelling nailing implement, a rigid frame for moving support on the work, front and 50 rear handles on the frame for use in manipulating the implement over the work, a nail-driving hammer, a spring means constantly and yieldingly operative to resist a disposal of the hammer in a predetermined position from which a working stroke of the hammer is to be effected, a control means for the hammer repetitively operative to dispose the hammer in said position and thereupon release it for its working strokes under the influence of the spring, a power drive for said control means, a normally engaged releasable clutch connection between the control means and the power drive, and means operable by an operator's hand grasping the forward said handle for guiding the implement to release said clutch.

5. In a nailing unit of the type described, a head block having an upright guide bore extending therethrough, a normally raised nail-driving plunger slidably engaged in said bore for its depression to drive a nail disposed below it in the bore, a hammer for actuation to effect a nail-driving depression of the plunger, a nail-inlet passage extending downwardly from a point on a block side to the bottom portion of the guide bore for delivering a nail in upright position beneath the raised plunger in the latter bore, a

slideway providing a line of uprightly disposed nails terminating at the inlet end of the nail inlet passage, a member operative as a gate while the plunger is raised to admit the leading nail from the line to the nail inlet passage while holding back the remaining nails, and a cam means directly operative to alternately actuate the hammer and gate member.

6. In a travelling nailing machine, a rigid frame, a head block fixedly mounted on the frame and having an upright bore extended therethrough, a normally raised and depressible plunger for actuation against a nail disposed therebelow in the head block to drive the nail, a swinging hammer having its handle pivotally mounted on the frame and arranged for the action of its head against the head of said plunger to drive the nail therewith, a spring means constantly and yieldingly operative to resist a swinging of the hammer to a predetermined position from which a working stroke of the hammer against the plunger is to be taken, a gear and lever connection between the hammer handle and spring, means directly operative against the hammer handle to dispose the ham-

mer in said limiting position and thereupon release it for a working stroke under the influence of the spring, and means to actuate said last means.

5. In a travelling nailing machine, a frame, a head block fixedly mounted on the frame and having an upright bore extended therethrough, a normally raised and depressible plunger for actuation against a nail disposed therebelow in the head block to drive the nail, a swinging hammer having its handle pivotally mounted on the frame and arranged for the action of its head against the head end of said plunger to drive the nail therewith, a spring means constantly and yieldingly operative to resist a swinging of the hammer to a predetermined position from which a working stroke of the hammer is to be taken, means adjustable to adjust the effective spring resistance, and means for actuation against the hammer handle to dispose the hammer in said limiting position and thereupon release it for a working stroke under the influence of the spring.

JOHAN A. JOHANSSON.
